COATED ELECTRICAL CONDENSER

Filed July 6, 1944

UNITED STATES PATENT OFFICE

2,512,874

COATED ELECTRICAL CONDENSER

Julian L. Reynolds, Richmond, Va.

Application July 6, 1944, Serial No. 543,722

1 Claim. (Cl. 175—41)

1

This invention relates generally to electrical condensers of the type in which individual sheets or the convolutions of a coiled sheet in the form of a continuous roll of a metallic conducting material, usually aluminum, are separated from one another by the use of a nonconducting or dielectric material. The dielectric insulator may be either (a) individual sheets or a long continuous coiled length of the dielectric material, usually paper, or (b) a dielectric coating applied to both surfaces of the individual sheets or continuous length of aluminum foil. More particularly, the invention relates to the latter (b) type of dielectric coated condensers.

In constructing the first mentioned type of aluminum-paper dielectric condensers, the individual sheets or the continuous coiled length of the paper dielectric are wider than the individual sheets or continuous length of aluminum foil and extend beyond the edges thereof, so that the electricity accumulated in the condenser will be prevented from jumping from the edge of one aluminum sheet or convolution to adjacent ones. Manifestly, this manner of insulating the exposed edges of the aluminum foil by extending the dielectric pellicle cannot be applied to the dielectric coated type of condenser which dispenses entirely with the need of a dielectric separate and apart from the aluminum foil. As a result, condensers of the coated type have proven unsatisfactory due to the tendency of the accumulated electricity to jump from the edge of one aluminum pellicle to the other and thus dissipate the current and lower the electrical capacity of the condenser.

One of the objects of this invention is to overcome this shortcoming in the dielectric coated type of condenser. This is achieved by a peculiar and novel arrangement of the individual sheets or continuous length of the metallic foil, after these have been coated to provide the required dielectric insulation, as will be fully described hereinafter.

Another object of this invention relates to the compositions used in forming the dielectric coating, and to improved processes for applying the coating and for improving the performance of the condenser.

For the attainment of the foregoing and such other objects of invention as may herein appear or be pointed out, I have shown a number of embodiments of my invention in the accompanying drawing, wherein—

Figure 1 is a cross sectional view of one form of my invention in its simplest or unit form comprising a four-ply lamination.

Figure 2 is likewise a cross sectional view of another form of my invention as employed in built-up form in a condenser having greater electrical capacity.

Figure 3 is also a cross sectional view of another form of built-up condenser lamination.

Figure 4 is a perspective view, somewhat diagrammatically shown, of the application of the invention to the formation of a long continuous length of condenser lamination adapted to be subsequently coiled or cut in making the condenser.

As mentioned in the statement of invention above, a serious difficulty has been encountered, in the coated type of condenser, in preventing the electricity accumulated in the condenser from bridging across the edges of adjacent sheets or convolutions. I have overcome this shortcoming in coated condensers in a manner which will be best described with the aid of Figure 1, which shows this aspect of my invention in its simplest form. There are shown two condenser elements designated 10 and 20, each condenser element being constituted of a foil or sheet of a metallic conducting material, 11 and 21, respectively, covered on their both surfaces with a dielectric coating, designated 12 and 13 in the case of element 10, and 22 and 23 in the case of the other condenser element 20. Both condenser elements 10 and 20 are U-shaped and interlocked or interleaved in the manner shown in Figure 1 with the pellicle portion of one element, e. g., pellicle portion 20a of element 20, received between the spaced pellicle portions 10a and 10b of the other condenser element 10.

The web portion of one condenser element prevents the accumulated electricity from jumping across the distal edges of the spaced pellicle portions of the other condenser element. That is, the web portion 20w of condenser element 20 prevents the bridging of the accumulated electricity across the distal edges of the pellicle portions 10a and 10b of condenser element 10. Web portion 10w of element 10 prevents the jumping of accumulated electricity from the distal edge of pellicle portion 20a of element 20 to the edges of adjacent condenser elements (not shown in Figure 1) where the four-ply lamination unit (pellicle portion 10a—20a—10b—20b) are built-up to form increased condenser capacity.

The inventive thought described in its simplest terms in Figure 1 in connection with a four-ply pellicle unit may be applied in various ways to form condensers of increased capacity; one suitable arrangement is shown in Figure 2, another appears in Figure 3. Referring first to Figure 2, it will be seen that the condenser elements are of S-shape, two such S-shaped elements being shown in full, viz., 40 and 50. The elements are interlocked or interleaved in the manner shown in Figure 2. Thus, the pellicle portion 40a of element 40 is received between the spaced pellicle portions 30b and 30c of element 30 (only partially shown). On the other hand, pel-

licle portion **30c** of element **30** is received between the spaced pellicle portions **40a** and **40b** of element **40**, while the other pair of spaced pellicle portions **40b** and **40c** of element **40** receive between them pellicle portion **50a** of element **50**.

The web portions, e. g., **40w** and **40w¹** of element **40** and **50w** and **50w¹** of element **50**, prevent the accumulated electricity from jumping across the edges of the condenser elements in the manner described above in connection with Figure 1. Another form of built-up condenser elements employing the principle of my invention is shown in Figure 3. This form uses U-shaped elements, three such U-shaped elements, **28**, **18** and **29** being shown in full in Figure 3 and two other elements, **17** and **19**, only partially.

My invention may be applied to the continuous roll type of coated condenser, in the manner shown in Figure 4. Two rolls **14** and **24** of the metallic conductor foil are provided, both surfaces of the foil being coated with the dielectric material. The width of the foils unwound from rolls **14** and **24** is sufficient to permit each of the foils to be bent back on itself to form a U-shaped element, respectively **10¹** and **20¹**, the two elements being interleaved in the manner described above in connection with the simple unit, Figure 1, of four-ply laminations. As clearly shown in Figure 4, the two rolls **14** and **24** are displaced longitudinally from one another so that the unwound continuous webs **15** and **25** from the respective rolls will overlap a predetermined extent, designated **a** in Figure 4. Foil web **15**, which is positioned higher in Figure 4, is turned down or bent 180° upon itself, starting at point A, to form the U-shaped condenser element **10¹** with the overlapped portion **a** of the other foil web received between its pellicle portions. Condenser element **10¹** thus forms an inverted U. The other foil web **25** is then turned upwardly, at a point B beyond the said point of turning A of foil web **15**, to form the upright U-shaped element **20¹**.

In this manner a four-ply interlocked lamination may be made which may be used in its continuous length to form the convolution type of condenser, or which may be cut into short lengths for use in the type of condenser comprising a plurality of spaced sheets.

I have found the following substances suitable for the dielectric coating: cellulosic materials, such as nitro-cellulose, cellulose acetate, etc., which may be used alone or together with waxes, resins, etc.; phenol formaldehyde, the vinyls and poly vinyls, such as vinyl chloride, acetate, styrene, butyral, etc.; combinations of rubber, rubber chlorides, etc.

I have found that the addition of such materials as ethyl cellulose to my dielectric coating, when this is compatible with the other ingredients, will lend durability and toughness to the coating and prevent scuffing or abrasion of the coating which would reduce its physical strength or destroy its dielectric properties.

Where the dielectric coating which I add to the surfaces of the condenser foil or the method by which it is necessary to apply it will not permit of treating a very thin foil, say of .00015" caliper, I first apply a thin paper tissue to either one or

both surfaces of the foil. The dielectric coating material, such as those enumerated above, serves as an adhesive to bind the tissue to the condenser pellicle element. When greater dielectric strength is desired, I coat the combined lamination of tissue and condenser foil or sheet with another protective coating which may be either the dielectric resinous or rubber coating or may be a coating of pure wax or wax combination.

After my condensers are so made by the methods herein outlined, I may subject them to a bath or to a coating which tends to prevent moisture or harmful gases or other agents from attacking the condenser. I have found asphaltum best suited for providing a water-resisting covering. It is understood that condenser foil when subjected to various chemical or electrical treatments such as anodizing electrolysis are also included in the scope of my invention. This may include the treatment of aluminum with sodium hydroxide or other alkaline earthy hydroxides, or it may also include acid etching treatments whereby the total exposed surface of a given square area of sheet is greatly increased due to the finely pitted surface of the foil. In order to accomplish this, electrolysis may be used whereby portions of the surface of the metallic condensing foil are removed in suitable electrolytic baths.

Having described my invention, what I claim and desire to secure by Letters Patent, is as follows:

A coated electrical condenser consisting of a plurality of foil sheets, of a metallic conducting material covered on both of its surfaces with a dielectric coating, each sheet being bent into U-shaped formation, and successive sheets being reversed in position and interleaved in such manner that each U-shaped dielectric sheet receives and encloses the legs of two associated sheets, the distal edges of the associated sheets thereby being shielded, and the structure reinforced by the interleaving, the interleaved legs of the various sheets being substantially equal in length.

JULIAN L. REYNOLDS.
